O. Martin
ATTORNEY

UNITED STATES PATENT OFFICE.

KONRAD JONASSEN, OF TENINO, WASHINGTON.

COMBINATION ROCK DRILL AND REAMER.

1,034,803.

Specification of Letters Patent.

Patented Aug. 6, 1912.

Application filed May 7, 1912. Serial No. 695,759.

To all whom it may concern:

Be it known that I, KONRAD JONASSEN, a subject of the King of Norway, and resident of Tenino, in the county of Thurston and State of Washington, have invented certain new and useful Improvements in Combination Rock Drills and Reamers, of which the following is a specification.

My invention relates to means for sinking holes or pockets into rocks, such pockets to serve as receptacles for charges of explosives introduced for the purpose of splitting or otherwise dismembering the said rocks.

15 In order to obtain blocks or slabs of particular shape from a solid rock formation it is necessary to provide means tending to cause the rock to part along certain predetermined lines. This is usually accomplished by sinking a row of holes into the rock along the desired parting line, and by reaming the said holes to a peculiar shape adapted for the purpose specified.

25 The object of my invention is to provide a simple and efficient device for producing the aforesaid results. More specifically my aim is to combine such drilling and reaming apparatus in one tool, thereby not only saving time of operation but materially simplifying the operation, as will hereinafter be fully explained.

35 In the accompanying drawing, forming part of the specification, Figures 1 and 2 illustrate in front and side elevation a rock drill embodying my invention. Fig. 3 is an end elevation of the drill. Figs. 4 and 5 are cross sectional views taken through the center of Figs. 1 and 2 respectively. Fig. 6 shows a cross section on line C—C of Fig. 2. 40 And Fig. 7 illustrates the method of operating upon a rock formation.

My device comprises a shank 1 of any suitable shape and length and made at one end with an enlarged portion or head 2. A 45 central perforation 3 extends the entire length of the device, and through this perforation air is admitted for the purpose of blowing the accumulating rock dust away from the cutting face of the apparatus.

50 The drill proper is composed of a series of radially disposed teeth 4. The shape of said teeth may be varied to suit operating conditions, but I have found the shape illustrated in the drawing to give entire satisfaction. It is noticed that the cutting edges,

5, of the said teeth are of the same height, thus presenting a perfectly level cutting surface.

The head 2 flares out on opposite sides and terminates in two segmental cutters 6, 7, 60 the cutting edges, 8, of which are positioned somewhat behind the drill surface 5. Said segmental cutters form the reamers of my device, and are provided for the purpose of producing a smooth wall in the pockets. Intermediate said reaming cutters are a pair of comparatively narrow projections 9, made with a high inner edge 10, a low outer edge 11, and adjacent, slanting edges 12. These projections, or side cutters, serve to cut narrow grooves in the wall of the pockets for the purpose of directing the parting of the rock operated upon, as indicated in Fig. 7. In this view 13 represents a rock formation, into which a series of pockets 14 have been 75 sunk. The grooves, 15, of said pockets all point in direction of line 18, when therefore charges, placed in said pockets, are exploded, the rock will part substantially on said line.

80 The operation of my device is clear to any one versed in the art, and one advantage of the apparatus is that the drilling and reaming operations are combined, whereby considerable time is saved. Another advantage 85 is that the apparatus is fed into the rock without resorting to the usual turning movement, which is not only difficult but very tiresome and fatiguing. Finally the head of my device, due to the liberal curve, 19, 90 cuts entirely free, so that it does not stick and can be removed from the sockets without any material effort on the part of the operator.

I claim:

1. In a device of the character described, in combination, a body comprising a shank and an integral head, said body having a central perforation, the face of said head having radially disposed drill teeth concentric with said perforation, a pair of concentric, segmental reaming lips positioned on opposite sides of said head, and a pair of side cutters intermediate said reaming lips, all for the purpose set forth.

2. A rock drill comprising a hollow body portion flaring at one end to provide clearance in cutting, said flared portion terminating in a pair of segmental reaming cutters, a face drill centrally positioned on said

head, and a pair of narrow side cutters intermediate said segmental reamers, all for the purpose set forth.

3. In a rock drill, a body perforated 5 through the center and terminating at one end in a flaring head, drill teeth radially disposed on the face of said head and concentric with said perforation, concentric and segmental reaming cutters encompassing 10 said drill teeth and having their cutting face on a lower plane than the face of said teeth, and a pair of narrow side cutters intermediate said reaming cutters, said side cutters having a wide flare so as to cut deep 15 grooves in the wall of the hole to be sunk.

4. In a rock drill, a centrally perforated

body having at one end a flaring head, stepped cutters on the face of said head, said cutters comprising an inner circle of radially disposed drill teeth, segmental 20 reaming cutters arranged on an outer circle, and a pair of narrow, slanting side cutters positioned in the spaces between said segmental cutters, all substantially as set forth.

In testimony whereof, I have hereunto affixed my signature in the presence of two witnesses.

KONRAD JONASSEN.
